UNITED STATES PATENT OFFICE.

EMILE G. PERROT, OF PHILADELPHIA, PENNSYLVANIA.

BUILDING.

Application filed May 27, 1925. Serial No. 33,084.

My invention has for its object the construction of a building in which one or more of its floors are provided with drainage passages substantially parallel to the floor surface and draining into one or more transverse conduits, and whereby communication may be had with said drainage passages from apparatus or machines at different places upon the floor by forming communication through the floor into the drainage passages wherever needed.

The utility of my invention is especially advantageous in buildings in which large quantities of solutions are employed, such as in dye house equipments, and of which much waste fluids arise that have to be discharged to the sewer, my improvements being adapted to permit removal of such waste fluids without the clogging up of the floor space or the ceilings of the next floor below, with exposed pipes, etc. In many modern manufacturing plants, the "dye house" equipment is arranged in the upper floor of the building and my improved floor structure lends itself to perfect drainage, clean dry floors, unobstructed working space and confining all the passages and conduits within the floor so that they are practically unseen. My invention also insures more free drainage area and easy access thereto than where metal piping is employed; and moreover, the floor structure may be made relatively light in weight, strong in its design, and practically devoid of rustable fittings.

My improvements are adapted to buildings which are formed of structural iron work with concrete floors and also for buildings made entirely of reinforced concrete, and more particularly, the invention consists in a concrete floor having a plurality of parallel drainage passages whose horizontal areas equal a large part of the floor area above them, said drainage passages opening at their ends into one or more transverse drainage conduits whose bottom portions extend below the drainage passages and have communication with the drainage pipe or other means for removal of the collected fluids in said conduit and received from the drainage passages.

My invention also comprehends details of construction which, together with the features above enumerated, are fully described hereinafter and more particularly defined in the claims.

Referring to the drawings: Fig. 1 is a

vertical section through a floor portion of a building, employing structural iron work and embodying my improvements, taken on line 1—1 of Fig. 2; Fig. 2 is a vertical section of the same taken on line 2—2 of Fig. 1; Fig. 3 is a vertical section of the same taken on line 3—3 of Fig. 2; Fig. 4 is a vertical section taken on line 4—4 of Fig. 5, embodying my improvements as applied to a reinforced concrete building; and Fig. 5 is a vertical section taken on line 5—5 of Fig. 4.

Referring to Figs. 1, 2 and 3, which show my improvements as applied to a building employing structural iron work with concrete floors, 20, 21 and 22 represent the posts, beams and girders of the structural iron work and what is shown is only by way of illustration and may vary according to the design of the building.

2 is the concrete floor structure having the floor surface 3 and the lower layer 5 which may be reinforced by expanded or woven metal indicated at 15 near the lower part 80 and which would constitute the ceiling of the floor below. At one or more places across the floor structure is a drainage conduit 7 whose lower part 7^a is preferably inclined to drain the fluid accumulations to waste drain pipes 11 and 12 leading to the sewer. The drainage conduits 7 extend downwardly preferably below the level of the bottom part 5 of the flooring, as clearly indicated in Fig. 2, and may also open upward as at 8 to the floor level 3. The upper edges of the openings 8 to the conduits are provided with longitudinal Z-shaped irons forming grooves in which removable floor plates 10 are fitted. By removing the said plates 10, access is had to the interior of the conduit for cleaning purposes when necessary. The floor structure is provided with a plurality of drainage passages 4 which may conveniently be formed of hollow tile 100 arranged end to end in parallel relation in a plane substantially parallel to the surface 3 of the floor, and the ends of the said parallel drainage passages 4 open at 6 into the chamber 8 and by which they discharge into the drainage conduit 7. These drainage passages 4 are preferably arranged on a slight incline, as shown, so that the flow by gravity is insured with a discharge into the conduit. To prevent any escape of water or moisture downward from the drainage passages to the ceiling portion 5 of the floor,

Referring to the drawings: Fig. 1 is a

an impervious layer 13 may be provided and this may be of asphaltum building paper upon which the drainage tiles making up the passages 4 are placed, as indicated more fully in Figs. 2 and 3. The concrete layer 2 rests upon the hollow tile and extends down between the same as at 2^a forming, as it were, ribs between the tile and these may be reinforced by metal rods 2^b, (Fig. 3).

16 In constructing these floors, the lower part 5 of the same, together with the reinforcing metal 15, is constructed upon wooden forms suspended from the structural iron work, and these portions may be continued 18 between the girders 22, as at 19, with the reinforcing expanded or other metal part 16 so that the conduit 7 is strong and durable. The interior of the conduits may be made 20 water tight by use of asphaltum or other suitable means familiar to the building trade, if so desired, and I do not limit myself in matters of details of this character.

14 indicates the use of asphaltum paper lining the upper walls of the conduit about 25 the ends of the passages 4 and such paper protection may be extended downward into the lower conduit portion 7, if so desired.

As shown in Fig. 2, the conduit 7 is transversely arranged with respect to the longitudinal alignment of the drainage passages 4 and, moreover, drainage passages are arranged upon opposite sides of the conduit and discharge thereinto, so that each conduit 30 7 may receive drainage from a large number of passages 4 located at one side or both sides according to the general construction of the building. In Fig. 1, moreover, it will be observed that where the structural iron girder 21 would block a continuation of the drainage conduit 7, the said conduit may be divided with the incline such that the fluid contents in the two sections would drain toward the girder and adapted to be drained off by the drainage pipes 11 which communicate 35 with the common drain pipe 12.

The drainage passages 4 are arranged conveniently close to permit an aperture to be formed almost anywhere through the floor 2 for drainage into one or more of the drainage passages, as shown at the upper right hand portion of Fig. 2, wherein an aperture is provided at 17 and through which a drainage pipe 18, leading from the tanks or vats or other source, may be extended. Similar 40 openings may be made wherever the apparatus employed in the room may necessitate and in this manner permit immediate discharge of waste fluids such as occurs in bleaching and dyeing establishments and 45 others where waste fluids in quantity must be gotten rid of.

It will be manifest that where immediate connection may be made with a drainage passage within the floor structure that the general equipment in the room may be greatly

simplified and, furthermore, that the necessity of supporting from the ceiling of the floor below of numerous drain pipes may be entirely avoided so that not only is the room above the floor clear of objectionable 70 piping adjacent to the floor, but similarly, the room below the floor may be equally clear of piping and suspension means adjacent to its ceiling.

Referring now to Figs. 4 and 5, the construction here shown corresponds in general particulars to that embodied in Figs. 1, 2 and 3, but as the improvements are shown in connection with an all-concrete building, the presence of the iron structural work is omitted and in this case the conduits 7 may be continuous, so that only one drainage outlet 11 will be necessary for each conduit of a reasonable length. Otherwise, the general features of construction are the same in respect to the drainage passages in the floor structure and their method of communication with the conduits.

Referring, however, to Fig. 5, it will be seen that the drainage passages 4 are inclined to the right and to the left from point 4^a, the waste fluid which passes to the right discharging into another drainage conduit (not shown) which would be in parallel relation to and correspond in structure to the conduit 7, the connection with such additional conduit being the same as shown at the left hand side of said Fig. 5 (or Fig. 2). In this manner, the length of the passages 4 may be a maximum and the number of transverse drainage conduits a minimum for a given floor area; and in such an equipment, should the passage 4 leading into one conduit 7 become clogged from any cause, the water would flow in the other direction over the high level and to the next adjacent conduit, thereby reducing the possibility of defective drainage.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having thus described my invention, what I claim and desire to secure by Letters Patent is:

1. A floor construction for buildings, comprising upper and lower concrete layers respectively forming the floor at one level and the ceiling at a level immediately below, said layers spaced apart and providing between them a plurality of drainage passages having side walls integrally united with the

upper layer and providing downwardly extending girder portions reaching to the lower layer, and a drainage conduit arranged transversely to the drainage passages and formed of concrete integrally connecting with the lower concrete layer and having its lower part extending to a level below the drainage passages and provided with means for draining the water and accumulations therefrom.

2. The invention according to claim 1, wherein further, the drainage passages are formed in parallel alignment and the intermediate downwardly extending concrete girder portions are reinforced.

3. A floor construction for buildings, comprising a concrete floor having a plurality of drainage passages arranged in a general plane substantially parallel to the surface 20 of the floor, said drainage passages opening into a transverse drainage conduit whose lower part extends to a level below the drainage passages and provided with means for draining the water and accumulations 25 therefrom, and wherein further, the drainage passages are each formed of tubular tile arranged end to end so that the passage is inclined sufficient for drainage purposes, and said tile resting upon a water proof 30 layer interposed between it and the lower body of concrete and said floor having concrete bodies interposed between the tile drainage passages and integral with the concrete above said tile passages.

4. A floor construction for buildings, comprising a concrete floor having a plurality of drainage passages arranged in a general plane substantially parallel to the surface of the floor, said drainage passages opening into a transverse drainage conduit whose lower part extends to a level below the drainage 45 passages and provided with means for draining the water and accumulations therefrom, and wherein further, the transversely arranged drainage conduit opens upwardly through the floor and is provided with removable closures.

5. A floor construction for buildings, comprising a concrete floor having a plurality of drainage passages arranged in a general plane substantially parallel to the surface of the floor, said drainage passages opening into a transverse drainage conduit whose lower part extends to a level below the drainage 55 passages and provided with means for draining the water and accumulations therefrom, and wherein further, the floor is provided with a vertical aperture so positioned that it provides an opening downwardly from the

floor surface into one of the drainage passages at a distance from the transverse conduit.

6. A floor construction for buildings, comprising a concrete floor having a plurality of drainage passages arranged in a general plane substantially parallel to the surface of the floor, said drainage passages opening into a transverse drainage conduit whose lower part extends to a level below the drainage 65 passages and provided with means for draining the water and accumulations therefrom, and wherein further, the concrete adjacent to the lower part of the floor structure and below the drainage 70 passages is reinforced with metal and said reinforcement extending downward and under the transverse drainage conduit, whereby the said conduit extends below the floor structure and is supported thereby.

7. A floor construction for buildings, comprising a concrete floor having a plurality of drainage passages arranged in a general plane substantially parallel to the surface of the floor, said drainage passages opening into a transverse drainage conduit whose lower part extends to a level below the drainage 85 passages and provided with means for draining the water and accumulations therefrom, and wherein further, the transverse drainage conduit is formed with an inclined bottom having its lowest part in communication with the waste drainage means.

8. A floor construction for buildings, comprising a concrete floor having at intervals apart deep parallel conduits and a plurality of intermediate drainage passages arranged transversely to at a higher level than the drainage conduits and opening at their opposite ends into the respective adjacent 95 drainage conduits, said drainage passages being spaced at a distance from each other and in a general plane substantially parallel to the floor surface, each of said drainage passages having their ends inclined downward 100 from an intermediate portion and normally draining in opposite directions into the respective drainage conduits, and whereby in case of stoppage of either inclined portion to its drainage conduit the overflow therefrom will automatically discharge through the other inclined portion into the other drainage conduit, and waste pipe connections 110 from the drainage conduits.

In testimony of which invention, I hereunto set my hand.

EMILE G. PERROT.
